AUTOMOBILE FLOOR MAT AND THE LIKE

William C. Gerber, Wooster, Ohio, assignor to Rubbermaid Incorporated, Wooster, Ohio, a corporation of Ohio

Filed Feb. 11, 1969, Ser. No. 15,738

Term of patent 14 years

Int. Cl. D12—14

U.S. Cl. D14—5

1 is a top plan view of an automobile floor mat like embodying my new design.

2 is a fragmentary top perspective view thereof.

3-6 are enlarged fragmentary sectional views of lines 3-3, 4-4, 5-5 and 6-6, respectively, 1.

1: ornamental design for an automobile floor mat like, substantially as shown.

UNITED STATES PATENT OFFICE
CERTIFICATE OF CORRECTION

Design No. 217,447

May 5, 1970

William C. Gerber

It is certified that error appears in the above identified patent and that said Letters Patent are hereby corrected as shown below:

Column 1, line 1, beginning with "1 is a top" cancel all to and including "as shown." in line 9, same column 1, and insert:

FIG. 1 is a top plan view of an automobile floor mat and the like embodying my new design.

FIG. 2 is a fragmentary top perspective view thereof.

FIGS. 3-6 are enlarged fragmentary sectional views taken on lines 3-3, 4-4, 5-5 and 6-6, respective, of FIG. 1.

I claim:

The ornamental design for an automobile floor mat and the like, substantially as shown.

Signed and sealed this 15th day of December 1970.

(SEAL)
